UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
ENGLAND.

BREECH-ACTUATING MECHANISM OF SEMI-AUTOMATIC AND QUICK-FIRING GUNS.

1,088,211.

Specification of Letters Patent. Patented Feb. 24, 1914.

Application filed April 1, 1912. Serial No. 687,576.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Breech-Actuating Mechanism of 5 Semi-Automatic and Quick-Firing Guns, of which the following is a specification.

This invention relates to the breech actuating mechanism of semi-automatic guns of the kind that can be converted into quick 15 firing guns; in this type of gun we have already proposed to provide two catch devices one of which is adapted to lock the breech actuating hand lever to the gun when the latter is to be worked semi-automatically 20 and the other to lock the hand lever to the block actuating spindle when the gun is to be worked as a quick firer.

According to the present invention we so 25 construct and arrange the said catch devices that the one for causing the hand lever to be locked to the actuating spindle cannot be moved into its locking position without effecting the disengagement of the other 30 catch device. In this manner it is impossible when the gun is working semi-automatically 35 for the parts to be damaged as a result of the hand lever being unintentionally locked to the gun and to the actuating spindle at the same time. The connection between the catch devices is also such that the 40 catch device for locking the hand lever to the gun is capable of being disengaged without disturbing the catch device appertaining to the actuating spindle, so that if the breech 45 block should fail to return to the closed position when the gun is working semi-automatically, the actuating hand lever can be moved into a position such that the last mentioned catch device engages with the 50 actuating spindle, whereupon the latter can be moved by hand. The last mentioned catch device is preferably made in the form of a pivoted lever carried by the actuating hand lever; it is normally retained disengaged from the actuating spindle and is adapted to move into engagement therewith by the act of grasping the handle of the hand lever. During this movement the said

pivoted lever, or a member appertaining thereto, effects the disengagement of the 55 catch device that locks the hand lever to the gun.

In order that the said invention may be clearly understood and readily carried into effect we will describe the same more fully 60 with reference to the accompanying drawings in which:—

Figures 1 and 2 are respectively an end and a side elevation, Figs. 3 and 4 are sectional end and side elevations, and Fig. 5 65 is a plan, showing one constructional form of our improvements. Figs. 6, 7, 8, 9 and 10 are views similar to Figs. 1, 2, 3, 4, and 5 respectively showing another constructional form of our improvements. 70

In all these figures like letters of reference indicate similar parts.

A is a portion of the breech end of the gun, B the breech actuating hand lever, B^x its handle and B' the block actuating spindle. 75

C represents the catch device for locking the hand lever to the actuating spindle (herein referred to as the "quick firing catch") and D represents the catch device 80 for locking the hand lever to the gun (herein referred to as the "semi-automatic catch").

In the type of breech actuating mechanism to which our invention is shown applied by 85 way of example, the actuating spindle B' is provided with a toothed segment B² that engages with a spring controlled rack contained in a case or cavity B³ forming part of the breech actuating hand lever B, in a 90 similar manner to that set forth in the specification of our British application for Patent No. 19,847 of 1910. The quick firing catch C is, in the examples shown, in the form of a lever pivoted at c to the hand 95 lever B, and its forward end is adapted to engage in a recess b² of the toothed segment B².

In the constructional forms of the invention shown, in which the improvements are 100 shown applied to an actuating hand lever the handle of which projects beyond the face of the breech, so that the semi-automatic catch D cannot conveniently be situated within the handle, the quick firing catch C 105 is adapted to be under the control of a

spring C', and is under the influence of a grip lever E carried by the handle as shown in the drawings.

The semi-automatic catch D is of the 5 spring controlled plunger type and is, in the examples now being described, carried by the gun and adapted to engage in a pocket B^o in the hand lever B. The said catch is under the influence of an operating lever F 10 pivoted at f to the hand lever and provided with an arm f' that bears against the semi-automatic catch D and with a projecting portion F' by which the said operating lever can be actuated.

15 The function of the various parts is such that it is impossible to cause the quick firing catch C to engage with the recess b² of the pinion B² without moving the semi-automatic catch D into the unlocking position,

20 while at the same time the semi-automatic catch D can, by means of the operating lever F, be moved out of engagement with the actuating hand lever without moving the quick firing catch.

25 Modifications of the broad idea herein disclosed are described and claimed in our divisional applications, Serial Nos. 760,350 and 760,351, filed April 11, 1913.

What we claim and desire to secure by 30 Letters Patent of the United States is:—

1. In the breech actuating mechanism of semi-automatic and quick firing guns, the combination with the breech actuating hand lever and the block actuating spindle, of 35 means for locking the hand lever to the gun, means for locking the hand lever to the spindle, and means for inter-connecting said locking means so that they cannot both be in their locking positions at the same time, and 40 means whereby the means for locking the hand lever to the gun can be disengaged without moving the other locking means.

2. In the breech actuating mechanism of semi-automatic and quick firing guns, the 45 combination with the breech actuating hand lever and the block actuating spindle, of a catch device for locking the hand lever to the gun, a catch device for locking the hand lever to the spindle, and means for inter- 50 connecting said catch devices so that they cannot both be in their locking positions at the same time, and means whereby the catch device for locking the hand lever to the gun can be disengaged without moving the other 55 catch device.

3. In the breech actuating mechanism of semi-automatic and quick firing guns, the combination with the breech actuating hand lever and the block actuating spindle, of a

catch device, means for normally retaining 60 said device out of engagement with the spindle, a second catch device for locking the hand lever to the gun, means whereby the grasping of the hand lever moves the first-mentioned catch device into engagement with the spindle, and moves the second catch device out of operative engagement between the lever and the gun, and means whereby the last mentioned catch device can be disengaged without moving the first men- 70 tioned catch device.

4. In the breech actuating mechanism of semi-automatic and quick firing guns, the combination with the breech actuating hand lever and the block actuating spindle, of a 75 toothed segment on said spindle, a catch device, means for normally retaining said device out of engagement with the segment, a second catch device for locking the hand lever to the gun, means whereby the grasp- 80 ing of the hand lever moves the first-mentioned catch device into engagement with the segment, and moves the second catch device out of operative engagement between the lever and the gun, and means whereby the last mentioned catch device can be disengaged without moving the first mentioned catch device.

5. In the breech actuating mechanism of semi-automatic and quick firing guns, the 90 combination with the breech actuating hand lever and the block actuating spindle, of a pivoted lever on the hand lever, a second pivoted lever on said hand lever arranged below the first mentioned pivoted lever, an 95 extension on said second lever, and a spring controlled plunger on the gun for engaging with the hand lever and in contact with said second lever.

6. In the breech actuating mechanism of 100 semi-automatic and quick firing guns, the combination with the breech actuating hand lever and the block actuating spindle, of a pivoted lever on the hand lever, a second pivoted lever on said hand lever, a grip lever 105 coöperating with the first mentioned pivoted lever, an extension on said second lever and a spring controlled plunger on the gun for engaging with the hand lever and in contact with said second lever.

In testimony whereof we affix our signatures in presence of two witnesses.

ARTHUR TREVOR DAWSON.
GEORGE THOMAS BUCKHAM.
